(57) **CLAIM**

The ornamental design for an electric bottle chiller, as shown and described.

DESCRIPTION

FIG. 1 is a rear perspective view of an electric bottle chiller showing my new design;

FIG. 2 is a front perspective view thereof;

FIG. 3 is a front elevation view thereof;

FIG. 4 is a left side elevation view thereof; and,

FIG. 5 is a rear elevation view thereof.

The article is an electric bottle chiller. The right side elevation is a mirror image of the left side elevation.

The broken lines are for illustrative purposes only and form no part of the claimed design.
